COMPACT PROVIDING FACIAL
ILLUMINATION

Kim Earl Rush, Beaverton, Oreg.

Application May 26, 1947, Serial No. 750,520

1 Claim. (Cl. 240—6.45)

1

This invention relates generally to compacts and particularly to an illuminated compact.

The main object of this invention is to provide an illuminated compact whereby the face of the user may be illuminated when using the compact, or the device may be employed as a safe-guard for pedestrians.

I accomplish this and other objects in the manner set forth in the following specification as illustrated in the accompanying drawing, in

10

which:

Fig. 1 is a perspective view showing the device when being used as a compact.

Fig. 2 is a plan of the device.

Fig. 3 is a transverse section taken along the line 3—3 of Fig. 2.

Fig. 4 is a longitudinal section taken along the line 4—4 in Fig. 3.

Fig. 5 is a section taken along the line 5—5 in Fig. 3.

Fig. 6 is a side elevation of the door actuating hinge.

Similar numbers of reference refer to the same or similar parts throughout the several views.

Referring in detail to the drawing, there is shown a somewhat rectangular frame 10 having a rectangular recess 11 formed therein provided with a false bottom 12, the space 13 beneath which can be used for any desired purpose by merely lifting out the false bottom 12 and its marginal sides 14.

The second recess 15, cylindrical in form, is disposed within the frame 10 and receives the dry cell 16 which registers with the base 17 of the electric lamp 18 whose electrode 19 is in alignment with the central electrode 20 of the cell 16. A spring 21 is interposed between the base 17 and the cell 16 and urges the electrodes 19 and 20 apart.

The cell 16 is slidably held within the recess 15 by means of the threaded cap 22 having mounted therein a button 23 having the enlarged head 24 which engages the end of the cell 16.

Pressure on the button 23 slides the cell 16 within the recess 15 engaging the electrodes 19 and 20, thereby energizing the lamp 18 through the spring 21.

There is formed in the frame 10 an inclined surface 25 against which is placed a reflector 26 which is substantially at 45 degrees with relation to the axis of the cell 16 and lamp 18. Directly in front of the reflector 26 is disposed a light conductor 27 preferably of clear material on the outer edges of which are disposed the red translucent coatings 28 and 29.

It can be seen that the light from the lamp 18 will be reflected by the member 26 and directed as a beam along the line indicated by the arrow 30 to the face 31 of the user.

2

Hinged to the frame 10 by means of the hinges 32 and springs 33 is a door or cover 34. On the inner side is mounted the mirror 35 and a suitable catch 36 may be employed without departing from the spirit of this invention.

It can be seen from the foregoing that this device is not merely a means for facilitating the application of cosmetics, but also affords an appreciable measure of protection if carried in the hand, since some of the light is disbursed in the form of a red band by passing through the translucent coatings 28 and 39.

I am aware that numerous forms of compacts have been made in the past and in some instances they have been equipped with means for illuminating the mirrors thereof, the light therefrom being directed against the face of the user. It is to overcome the objections to such devices that I have produced the compact above described.

20 I claim:

A compact of elongated rectangular form, one long side constituting the back, a mirror cover hinged along said back, said compact having a rectangular recess formed along the front thereof, a light conducting element mounted along one short side of said compact having a reflecting mirror at the rear end thereof, the front corner of said element being rounded, the top, bottom and right hand edges of said element having red translucent covering, a flash light mounted along the interior of the compact having its operating button projecting from the other short side of the compact and having its bulb facing said mirror, the mirror forming an angle of approximately 45° with relation to the axis of the light conducting element whereby light rays from said flash light will pass along said conducting element and be diverged from the rounded end thereof.

KIM EARL RUSH.
